Fig. 2

Fig. 4

Fig. 1 is a side perspective view of a strap buckle showing my new design, the side opposite thereto presenting an identical appearance;

Fig. 2 is an end elevational view thereof as viewed from the left of Fig. 1;

Fig. 3 is an end elevational view as viewed from the right of Fig. 1; and

Fig. 4 is a top plan view thereof.

The side opposite to the side illustrated in Fig. 1 is identical in design to the side illustrated.

I claim:

The ornamental design for a strap buckle, substantially as shown and described.
